UNITED STATES PATENT OFFICE.

EDMUND YEISER, OF NEWMANSTOWN, PENNSYLVANIA.

SULKY-PLOW.

SPECIFICATION forming part of Letters Patent No. 244,708, dated July 19, 1881.

Application filed May 25, 1881. (Model.)

To all whom it may concern:

Be it known that I, EDMUND YEISER, of Newmanstown, in the county of Lebanon and State of Pennsylvania, have invented certain new and useful Improvements in Sulky-Plows; and I do hereby declare that the following is a full, clear, and exact description thereof, reference being had to the accompanying drawings, and to the letters of reference marked thereon, which form a part of this specification.

This invention relates to certain improvements in sulky-plows, and it has for its objects to provide for conveniently depressing the plow so that it will properly enter the ground, for elevating it so as to pass over stones, stumps, or other obstructions, or to permit the apparatus to be transported from place to place, and to provide for readily adjusting the parts relatively so that the plow may be worked close up to a fence, wall, or hedge, as more fully hereinafter specified. These objects I attain by the apparatus illustrated in the accompanying drawings, in which—

Figure 1 represents a plan view of the plow raised, and Fig. 2 a side elevation with one wheel removed and the plow lowered ready for work.

The letter A indicates the axle, which is constructed of iron and bent downward at each end, as indicated by the letter B. One of the said ends B, at its extremity, is bent laterally and horizontally, and upon such extremity is journaled one of the driving-wheels C. The other bent end B has secured to it by means of a suitable square-shanked bolt, D, an adjustable slotted bar or plate, E, in the slot of which is secured the adjustable horizontal spindle F, on which the other driving-wheel C is journaled. The axle on the side over said adjustable wheel is formed with an upwardly and laterally extending arm, G, to which is pivoted a brake-lever, H, the shoe or block I of which is adapted to bear, when brought into position, upon the upper part of the periphery of the wheel. Said arm G is provided with a lateral projection, K, which holds the brake-lever up when not in use, so that the handle L thereof will be in convenient reach of the plowman. This handle is curved, as indicated by the let-

ter M, and is provided with two apertures, N, or a curved slot, by means of which it can be shifted so as be placed within reach, whether the operator is mounted on the seat or following the plow, the said handle being pivoted to the brake-lever at O in such manner that when shifted it may be secured in the desired position by means of the bolt P, which is adapted to pass through the apertures N or the curved slot.

The letter R indicates a knuckle-lever, one member of which is pivoted to one of the ends B of the axle and the other to a stud, S, on the tongue U of the apparatus. The said members are pivoted to each other at V, and one has an extension, W, adapted to set over the other when the members are brought in line and hold the two securely, in order to keep the plow in an elevated position.

The forward member of the lever is provided with an upright extension, A', against which the foot of the plowman is to be placed to operate the lever to raise and lower the plow.

B' indicates a set-screw adapted to bear against the angle-lever R when the plow is down and the members are at an angle with each other, its object being to keep the parts in proper place and transfer the strain or a portion of the weight of the plow to the tongue. The said set-screw passes through an extension on plate C', projecting laterally from the tongue.

The tongue is confined to the axle by means of the plates D' and the clips E', embracing said axle loosely, so as to permit the tongue to swing on the axle, and the plow-beam is secured to the axle by means of a bearing plate or strap, F', setting over said axle and bolted to the beam between the two plates D', secured to the tongue.

a' represents a sliding collar on the axle, and which is provided with a thumb or tightening screw.

To the forward part of the plow-beam is secured an adjustable clamp, G', through the upper part of which extends the tongue, the said clamp carrying a small wheel or caster, H', at its lower end, which supports the forward part of the beam when the plow is down and at work.

I' indicates a brace extending from the tongue

to the stud K', by which it is secured at one end. The other end extends to the upper bend of the axle at one side, to which it is bolted by means of a bolt, L'.

5 The forward end of the beam is provided with a clevis, M', and the rear end with a handle, N', the latter to assist in elevating and depressing the plow.

10 The slotted extension and adjustable spindle for the wheel at one side permit the plow to be properly adjusted as to depth and position.

The plowshare may be of any description, and is indicated by the letter P', being attached to the beam in any convenient manner.

15 Having thus described my invention, what I claim, and desire to secure by Letters Patent, is—

1. In combination with the bent axle A, the knuckle or jointed lever R, secured thereto and 20 to the plow-tongue U, the said lever being provided with an extension, W, on one member, which is adapted to engage the other member, substantially as and for the purpose specified.

2. In combination with the jointed lever R, 25 bent axle A, and tongue U, the set-screw B', adapted to bear against the lever, substantially as and for the purpose specified.

3. In a sulky-plow, the combination of tongue U, having at its rear end and attached thereto 30 plates D' D', with axle A, clips E' E', adjustable collar a', and stirrup F, which secures to the beam of the plow both the axle and tongue, all substantially as herein described.

4. In a sulky-plow, the combination of the 35 slotted and adjustable clamp G, having a colter or gage wheel attached to its lower end, with the tongue U and the plow-beam, substantially as and for the purpose set forth.

In testimony that I claim the foregoing as 40 my own I affix my signature in presence of two witnesses.

EDMUND YEISER.
